Frank Ledermann

UNITED STATES PATENT OFFICE

AUGUST HEIN, OF BROOKLYN, NEW YORK

BELT CARRIER

Application filed August 15, 1929. Serial No. 386,121.

The main object of this invention is to provide a belt carrier which is adapted to be suspended from the shirt material of the wearer in order to permit the trousers to be draped about the body with the belt in loose or untautened condition.

Another object of the invention is to provide a belt carrier provided with an anchor plate which is secured to the shirt material of the wearer and a frame suspended from an elastic band; the frame carrying a saddle in which the belt of the wearer is supported, the purpose of the device being to permit the utilization of a belt as an article of wearing apparel in a comfortable and easy position about the body.

The above and other objects will become apparent in the description below in which characters of reference refer to like-named parts in the drawing.

Referring briefly to the drawing, Figure 1 is a front elevational view of the belt carrier per se.

Figure 2 is a longitudinal, sectional elevational view of the belt carrier, the section being taken vertically through Figure 1 on line 2-2 to illustrate the cooperating parts of the device.

Figure 3 is a front elevational view of the belt carrier showing the same in locked position and suspended from the shirt material and supporting a belt as attached to a pair of trousers.

Figure 4 is an enlarged longitudinal, sectional elevational view of the band carrying frame showing the means of adjustably securing said band to the frame.

Figure 5 is a perspective view showing the hook member as attached to the flexible band.

Referring in detail to the drawing, the numeral 10 indicates an elongated anchor plate formed of some suitable material not susceptible to be corroded by the perspiration of the body. The obverse face of this anchor plate has its marginal edge chamfered. Projecting from the face of this anchor plate is a longitudinal nose 11 which is constricted mid-way of its height in order to have the nose form a flange-like obstruction to prevent the slipping out of place of a suspension plate

12 which, together with a substantially resilient finger 13 forms a bifurcated member adapted to be slipped over the constricted part of the nose 11.

The finger 13 is separated from the rest of the plate 12 by a slot 14 which, as previously stated, receives the constricted portion of the nose 11. Upon the free extremity of the finger 13, a small detent 15 is provided which serves as a saddle for receiving the free end 55 of a hinged closure hook 16. The plate 12 has an elongated slot 17 formed therein for a purpose which will be more fully herein-after described.

A belt carrier frame is suspended from the plate 12. This belt carrier frame comprises a relatively small apron also provided with a longitudinal slot 19. Said apron is provided with a downwardly extending ear 20 in which a plurality of spaced 60 apart rectangular openings 21 are formed.

A second member comprising a tongue 22 extends downwardly parallel to the ear 20 and at its lower end is bent upwardly to form a hook 23 in which the belt 37, worn about the torso, is saddled. The lower end of the ear 20 is formed into an eyelet or loop 26 in which the connecting member of a triangular member is secured. This member has a pair of diverging arms 24 and 25 70 whose ends are turned towards each other to provide an internal bearing for a glass or similar roller 27. One end 28 of an elastic band 30 is looped about the lower portion of the plate 12 after passing through slot 17. This band section 30 suspends downwardly and lies adjacent a guide strip 29 forming part of the apron 18 and lying adjacent to the latter and then returns after

passing around half the periphery of the roller continues upwardly as indicated by the numeral 31 and then passes through the slot 19 and has its end attached to the ear 20. The end 35 of the elastic band opposite to the looped end 28 is provided with a strip 80 of rigid material which is bent midway of this width to pinch the end of the band between the doubled over portion of the plate. This plate 32 has triangular depressions 33

therein and the material in the area of the 85 90 95 100

depressions pierces the fabric of the band and secures this plate member firmly to the end of the band. Intermediate the length of the plate member a hook 34 is formed which is adapted to cooperate with the ear 20 by engaging any of the rectangular openings 21 in an adjustable manner. The plate 12 below the position whereon slot 17 is formed is also divided or split to permit the insertion of the looped end 28 of the elastic band when replacement or assembly of the elastic band is desired.

The device is adapted to be suspended from the shirt material for the purpose of carrying the trousers in a comfortable position by engaging the belt which latter, in this case, would be used as an article of adornment. The saddle hook 23 supports the belt 37 trained about the torso outside of the trousers and guided between the belt loops 36. These members are used in pairs—one on each side of the body. The anchor plate 10 is placed in a desirable position on the inside of the shirt material of the wearer. The nose 11 deflects the shirt material about the nose and the bifurcated plate 12 is then slipped over the constricted portion of the nose on the outside of the shirt material.

The device is now ready for suspending the trousers in a comfortable position without the necessity of tautening the belt for the proper draping of the trousers. The plate is directly secured to the elastic band member by having a looped portion 28 passing through the slot 17 in the plate 12. The belt is supported in the saddle hook 23 and, since the trousers are coupled to the belt, these entire two units will be suspended in a resilient and yieldable manner by means of the flexible band. To adjust the tension of the adjustable band, the hook member 34 at one end of the elastic band is moved to one or the other of the plurality of rectangular openings 21 as will be obvious from a perusal of the drawings. To eliminate friction as much as possible, the elastic band where it is doubled rides about a roller 27 made of glass or some other suitable material. To insure that the trouser carrying member comprising the plate 12 the carrier frame and the elastic band will not become dislodged from the anchor plate, a lock is provided. This lock is provided with a detent 15 on the finger 13 of the bifurcated plate 12 which is cooperated with by a looped latch element 10 hinged at one corner of plate 12 and is so positioned as to span and close the open end of the slot 14.

It is to be noted that certain changes in form and construction may be made without departing from the spirit and scope of the invention.

I claim:

1. In a belt carrier an anchor plate, a nose

on said anchor plate, a bifurcated member engaging said nose, a belt carrying member, an elastic band suspending said belt carrying member from said plate, and means for locking said bifurcated member in engagement with said nose.

2. In a belt carrier, an anchor plate, a nose on said anchor plate, a bifurcated member engaging said nose, a belt carrying member, an elastic band suspending said belt carrying member from said plate, a hinged latching member mounted on said bifurcated member, said bifurcated member having a detent therein, said latch engaging said detent to lock said bifurcated member on said anchor plate and means for adjusting the tension of said elastic band.

3. In a belt carrier, an anchor plate, a nose on said anchor plate, a bifurcated member engaging said nose, a belt carrying member, an elastic band suspending said belt carrying member from said plate, an ear on said belt carrier having spaced apart rectangular openings therein, a hook member secured to said elastic band, said hook member being adapted to engage in any of the openings of said ear for adjusting the tension of said elastic band.

4. In a belt carrier, an anchor plate, a nose on said anchor plate, a bifurcated member engaging said nose, a belt carrying member, an elastic band suspending said belt carrying member from said plate, an ear on said belt carrier having spaced apart rectangular openings therein, a hook member secured to said elastic band, said hook member being adapted to engage in any of the openings of said ear for adjusting the tension of said elastic band, and means for releasably attaching said elastic band to said bifurcated member.

5. In a belt carrier, an anchor plate, a nose on said anchor plate, a bifurcated member engaging said nose, a belt carrying member, an elastic band suspending said belt carrying member from said plate, an ear on said belt carrier having spaced apart rectangular openings therein, a hook member secured to said elastic band, said hook member being adapted to engage in any of the openings of said ear for adjusting the tension of said elastic band, said bifurcated member having a divided slot therein, a closed loop on said band, said band being adapted to be releasably slipped into said slot thru the division thereof.

In testimony whereof I affix my signature.

AUGUST HEIN.
